Fishing Float Company, Inc., Richmond, Va., a corpora-
tion of Virginia

Filed Mar. 14, 1962, Ser. No. 179,754

5 Claims. (Cl. 206—89)

This invention relates to devices for displaying containers of merchandise, and more particularly concerns a hang-up display device with a pilfer proof slide cover box.

In the display of small packaged articles of merchandise certain problems are encountered among which are proper support for the containers and prevention of unauthorized access to the contents within the containers. These problems are intensified where the containers are of the readily removable cover type, and more especially of the slide cover box construction.

An important object of the present invention is to provide a new and improved merchandise display device.

Another object of the invention is to provide an improved hang-up display device especially adapted for merchandise containers having removably attachable covers.

A further object of the invention is to provide a new and improved hang-up display device including means for rendering slide cover boxes on display substantially pilfer proof.

Still another object of the invention is to provide a new and improved hang-up display device embodying a novel manner of supporting and connecting a container equipped with a removably attachable cover to a display support.

A still further object of the invention is to provide a display device embodying means for not only improving retention of a transparent merchandise container but also improving the effectiveness of display of the merchandise.

It is also an object of the invention to provide a simplified, more economical and more efficient sheet form or card type hang-up display device.

Other objects, features and advantages of the present invention will be readily apparent from the following detailed description of a preferred embodiment thereof taken in conjunction with the accompanying drawing, wherein

FIGURE 1 is a front elevational view of a hang-up display device embodying features of the invention;

FIGURE 2 is an enlarged fragmentary vertical sectional detail view taken substantially on the line II—II of FIGURE 1;

FIGURE 3 is a fragmentary sectional elevational detail view taken substantially on the line III—III of FIGURE 2;

FIGURE 4 is a horizontal sectional detail view taken substantially on the line IV—IV of FIGURE 1; and

FIGURE 5 is an illustrative exploded assembly view of the display device.

In the illustrative form of the invention depicted, a merchandise container 10 is assembled for display purposes with a sheet form hang-up device 11 conveniently and economically comprising a throw-away card made by die cutting it from thin gauge cardboard. Adjacent its upper margin the card 11 has an aperture 12 by which the device can be engaged upon a pin or hook on a display rack or board.

For providing a package in which the merchandise contents can be readily viewed by a prospective purchaser, the container 10 is preferably made from a transparent rigid plastic material. This provides, in effect, a blister

2

type package. However, the conventional blister pack required destruction of the container. Desirably the present container 10 is a reusable plastic box molded to provide a bottom wall 13 (FIG. 2), end walls 14 and side walls 15 (FIG. 4), thereby providing a generally rectangular receptacle. Reinforcing ribs 17 may be provided integrally across the bottom wall 13 and the side walls 15.

A generally flat cover 18 is provided for closing the container 10 and is desirably of the slide-on removable type having opposite side flanges 19 spaced apart to receive the free margins of the side walls 15 of the container therebetween and provided with inwardly opening longitudinal respective grooves 20 slidably engageable with respective outwardly projecting longitudinally extending rail rib flanges 21 on the side wall margins. Thereby, the cover 18 is slidably engageable into and out of closing relation to the container 10. At one end the flanges 19 are shorter than the cover whereby to afford a lead-in flange lip 22 projecting therebeyond on the cover to facilitate engagement of the leading end portion of the cover against the edges at one end of the container in orienting the cover for slide-on attachment to the container. At the opposite end of the cover an angular stop flange 23 projects in the same direction as the side flanges 19 and may be integral therewith for opposing the adjacent end flange 14 of the container to delimit the fully assembled, closing disposition of the cover 18 relative to the container. Adjacent to the flange 23 the cover 18 is provided with an inwardly projecting interlock nib or boss 24 which lockingly snaps over the adjacent edge portion of the end wall 14 to resist sliding off of the cover 18 until sufficient slide-off pressure is applied to the cover 18 relative to the container 10.

For supporting the container 10 on the panel or card 11, means are provided for attaching the container to the card without the need for any extraneous elements or materials such as adhesive or clips or similar devices. To this end, the supporting display card 11 is provided with an aperture 25 dimensioned complementary to the perimeter of the container 10 about the end and side walls 14 and 15 and adapted to receive the container therethrough with free tolerance. On the other hand, the dimensions of the aperture 25 are slightly smaller than the perimeter dimensions of the cover 18. Thereby, the body or container portion 10 of the box can be inserted partially through the aperture 25, with the bottom wall 13 parallel to the plane of the card 11, and the container is thus well supported in a vertical position by the card 11.

Unintentional displacement of the container 10 from the card 11, and more particularly out of the aperture 25 is precluded by providing on the card 11 retaining means engageable with the container. Advantageously, such means comprise at least one and preferably two retaining tabs 27 and 28 derived from material struck out in the formation of the aperture 25, and each connected integrally in one piece with the card 11 by an angular offsetting flange portion 29. As best seen in FIGS. 2 and 5, the retaining tabs 27 and 28 are formed with portions in substantially coplanar relation, and to project toward one another from respectively the upper and lower edges defining the aperture 25. The length of the offsetting connecting flanges 29 is somewhat less than the depth of the container 10.

In assembly, the container 10 is received within the aperture 25 of the card 11 with the bottom wall 13 projecting from the front face of the card and top or open end portion of the container projecting from the rear face of the card and engaging the tabs 27 and 28, and the cover 18 clamping the tabs against the top edge of the container. Referring to FIGURES 1 and 4, the tabs 27 and 28 are narrower than the container 10 so that they will fit freely

over the free edges of the end walls 14 against which the cover 18 presses the tabs contiguous the juncture of the tabs with the connector flanges 29. This effects a quite efficient retention of the container 10 since it can be moved to only the most limited extent, if at all, afforded by dimensional tolerances in the plane of the card 11, and unintentional displacement normal to the plane of the card is precluded by the tabs and their connecting flanges. In fact, removal of the container 10 from the card 11, without destruction of the tabs 27 and 28, can be effected only by first removing the cover 18 from the container.

In assembling the container 10 with the card 11, it is projected, before attachment of the cover 18, through the aperture 25 from the side of the card opposite to the tabs 27 and 28 until the edges of the end walls 14 engage the retaining tabs, substantially as shown in dash outline in FIG. 5. Conveniently such projection may be effected while the container 10 is resting upright upon an assembly table and placing the card in assembled relationship with the container. Then, the cover 18 is aligned with the top of the container as shown in dash outline in FIG. 5 and is slid into assembled relationship over the tabs 27 and 28 to complete the assembly.

In order to accommodate the interlock lug 24 of the cover, and to afford an additional interlocking of the container 10 relative to the retaining tabs, one of the retaining tabs, herein the retaining tab 27 at the normally upper end of the aperture 25, is provided with a clearance aperture 30 (FIGS. 2, 3 and 4) across the juncture between and partly within the contiguous portions of the tab 27 and its connecting flange 29. Through this arrangement, the interlock boss 24 freely clears through the aperture 30 into engagement with the end wall 14 of the container, and at the same time enters into interlocking relation to the tab 27.

By having the stop flange 23 of the cover at the upper end of the container 10 in the hanging display assembly, there is no possibility of the cover under any circumstance being accidentally dislodged downwardly. Furthermore, this arrangement makes it more difficult for surreptitious opening of the cover by a would-be pilferer while the container is on hanging display.

Pilfering is also discouraged by having the bottom 13 of the container at the front of the display, and the cover 18 at the back of the display afforded by the card and container assembly. For this purpose, the face of the card 11 from which the bottom of the container 10 protrudes is desirably provided with display advertising, merchandise identification, price indicia, and the like. This will assure hanging of the display assembly with that side toward the front.

In addition, display of the merchandise within the container 10 is enhanced by the opaque background afforded by the tabs 27 and 28 disposed alongside and over a substantial area of the inner face of the cover 18. For this purpose the tabs may be of any preferred coloration or white, contrasting with the merchandise. This has been found excellent for displaying small articles of merchandise such as fishing accessories on the order of fish line weights, fish hooks and other items of fishing tackle.

The purchaser can, of course, quickly and easily remove the display card 11 from the container 10 by disengaging and removing the cover 18, wherafter the cover is replaced and the container provides a handy accessory box for the contained articles.

It will be understood that modifications and variations may be effected without departing from the scope of the novel concepts of the present invention.

I claim as my invention:

1. In a display assembly, a hang-up supporting card, said card having an aperture therethrough receptive of a merchandise container, said card having projecting integrally in one piece therefrom material struck from said aperture and

comprising a pair of aligned tabs each of which has a tab portion in a plane with the opposite tab and an angular connecting flange joining it to the card, a container having a bottom wall and a peripheral wall received in said aperture with the bottom wall projecting from the face of the card opposite said tabs and with the edge of said peripheral wall of the container engaging said tabs,

said peripheral wall at the open end of the container having means thereon interengageable with a slide-on cover,

a slide-on cover engaging said means and closing the container and clamping said tabs against said peripheral wall,

and interlock means on said cover engageable with said peripheral wall to resist removal of the cover, one of said tabs having an aperture therein for clearing said interlock means and interlocking coacting with said interlock means.

2. In a display assembly of the character described, a hang-up card,

a merchandise container having a transparent bottom and a wall structure provided with slide-on cover retaining means,

a slide-on cover having means cooperable with said retaining means and provided with an interlock boss engageable in snap-on relation with the wall structure in the fully assembled relation of the cover with the container,

said card having an aperture therein substantially complementary to said wall structure and the container being mounted in said aperture with the transparent bottom projecting from one face of the card, said card having tabs thereon extending from said aperture into engagement between said cover and said container wall structure,

one of said tabs having an interlock aperture therein through which said interlock boss projects interlockingly.

3. In a display assembly of the character described, a merchandise container having

a removably attachable cover of larger perimeter than the perimeter of the container,

a display support of sheet form having an aperture therethrough substantially complementary to the perimeter of the container but smaller than the perimeter of the cover,

said container extending through said aperture and supported therein,

and tab means projecting from said support and engaged between said container and said cover and thereby retaining the container in assembly with the support.

4. In a hang-up display device,

a card providing a display support and having an upper end portion with means for hanging the card on a suspension device,

a container-receiving aperture in said card below said upper portion and aligned with said means for hanging the card,

a container having a bottom wall and peripheral means providing an edge about an opening into the container defined by the wall means,

said wall means being substantially complementary in outside dimension with and received through said aperture with said bottom wall projecting from one face of said card,

vertically opposed tabs extending from the edge defining said aperture and engaged over said edge of the wall means,

a cover engaged upon said wall means edge and clamping said tabs,

said cover having angular flange means engaging upper and side portions of said peripheral wall means and with the lower portion of the cover free for passing

the peripheral wall means in downwardly sliding on and upwardly sliding off relation, and means on the flange means and on said wall means for slideable interengagement to retain the cover against lifting away from said wall means, upward sliding removal of the cover being difficult and thereby discouraging surreptitious opening of the cover by a would-be pilferer while the container is hanging from a suspension device.

5. A hang-up display device as defined in claim 4, in which the cover has interlock means thereon coactive with the upper portion of the wall means to resist upward sliding movement of the cover relative to the container, and the upper tab having clearance opening for said interlock means.
